UNITED STATES PATENT OFFICE.

WALTER W. GROOMS, OF CLEVELAND, OHIO, ASSIGNOR OF ONE-THIRD TO RICHARD L. PEMELTON, OF CLEVELAND, OHIO, AND ONE-THIRD TO STEWART CHARLTON.

ATTACHMENT FOR INTERNAL-COMBUSTION ENGINES.

Application filed December 8, 1920. Serial No. 429,083.

To all whom it may concern:

Be it known that I, WALTER W. Grooms, a citizen of the United States, and a resident of Cleveland, county of Cuyahoga, and State of Ohio, have invented a new and useful Improvement in Attachments for Internal-Combustion Engines, of which the following is a specification, the principle of the invention being herein explained, and the best mode in which I have contemplated applying that principle, so as to distinguish it from other inventions.

The present invention relates as indicated, to attachments for internal combustion engines and more particularly to a device adapted to reduce the amount of fuel used during the operation of the engine and also to prevent the formation of carbon in the cylinders and on the spark plugs of such engines. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a view partly in elevation and in section showing my attachments as applied to an internal combustion engine; Fig. 2 is a plan view of the cover of one of the parts showing an electric switch carried thereon; Fig. 3 is a horizontal section on the line 3—3 Fig. 1; and Fig. 4 is a section through a valve adapted to supply water to one of the parts.

The device as shown in Fig. 1 is adapted to be attached to an internal combustion engine 1 and comprises a tank or receptacle 2 having a cover 3 suitably held thereon. Passing through the cover 3 is a pipe 4 having an L-shaped extension 5 adapted to lie adjacent the bottom of the receptacle 2. The L-shaped extension 5 of the pipe 4 is provided with a plurality of outlets 6 the function of which will be described later. The pipe 4 extends up through the cover 3 and is provided with a T-connection 7 from the two remaining openings of which extend pipes 8 and 9. The pipe 8 leads to an insulated box or container 10 in which is mount-

ed a violet ray tube or ozonizer 11. Surrounding the tube 11 is a cylinder or casing 12 of metal to which a lead wire 13 is connected, this lead wire 13 being attached to one terminal of a spark coil 14. A second lead wire 15 connects the lower end of the violet ray tube to the other terminal of the coil which may be connected to the battery of the car or to a separate battery which is not shown. An inlet pipe 16 is provided in the wall of the container 10 on the side opposite to that in which the pipe 8 enters and is adapted to permit the circulation of air about the tube 11 and the casing 12.

The pipe 9 is connected to the exhaust manifold 20 and is adapted to convey the burned gas or any necessary quantity thereof up to the entire amount, from the engine 1 through the T-connection 7 and the pipe 4 to the L-shaped end 5 thereof and there permitted to escape through the perforations 6 into the receptacle 2. The pipes 8 and 9 are provided with valves to regulate the proportions of flow through said pipes.

The receptacle 2 is adapted to contain water, the level of which is automatically maintained at a predetermined height. The receptacle 2 is provided with two openings 21 and 22 which are in line with two complementary holes 23 and 24 in a smaller receptacle 25 and are connected together by means of short lengths of pipe 26 and 27 secured in the holes 21 and 23, and 22 and 24 respectively. Mounted in the receptacle 25 are two wires or guides 50 so disposed that the upper ends of each are positioned one quarter of a revolution in advance of the lower ends thereby forming in effect a helical guideway for a float 28 which is slidably guided on such wires 50 by means of a retaining strip 29 carried by the float 28 and provided with holes 30 adapted to engage around the wires 50.

Rotatably mounted centrally of the receptacle 25 is a shaft 31 on which is slidably keyed the float 28 so that the said shaft will rotate therewith as the float is rotated yet will permit the float to slide up or down according to the amount of water in the receptacle 25. The shaft 31 is pivoted in the bottom of the receptacle 25 and passes through the cover 32 and has attached to the extending portion a contact arm 33 which is adapted to engage or contact with a terminal 34 carried by and insulated from the cover 32

when the water in the receptacles 2 and 25 drops below a predetermined level.

When the contact arm 33 engages the terminal 34 the electrical circuit closed by such engagement operates a valve 35 which is adapted to permit water to flow into the tank 2. This valve may be connected to a water pipe 61 communicating with the engine radiator so as to eliminate the use of a separate water supply tank if desired.

As shown in Fig. 4, the valve 35 comprises the usual ball check valve 36 with the addition of an electromagnet 37 mounted thereon. The core 38 of the magnet extends within 15 in the casing of the valve 35 and terminates a short distance above the ball 39 which will be made of material adapted to be attracted by the core 38 when excited. When the circuit is broken the ball 39 will drop back onto 20 the valve seat 40 and cut off the water inlet.

I have also provided a water tank 50' having a pipe 51 leading therefrom to the receptacle 2. The lower end of the pipe 51 terminates at the level of the water in 25 the receptacle 2 and this pipe is provided with a valve 52 adapted to regulate the flow of water therefrom. The tank 50' is airtight and is provided with a filler cap 53. As the water in the receptacle 2 drops below 30 the predetermined level water will drop from the tank 50' through the pipe 51 into the receptacle 2 being displaced by air from the receptacle 2 until the water again reaches a level to seal the lower end of the pipe 51.

35 Leading from the cover 3 of the receptacle 2 is a third pipe 60 which is connected to the inlet manifold 61 at a point above the carburetter 62. In operation my device works as follows: The circuit controlling 40 the coil 14 is closed thereby operating the violet ray tube or ozonizer 11. The operation of the engine creates a suction in the pipe 60 and a partial vacuum in the receptacle 2. This creates a suction in the pipe 45 and air is drawn through the inlet 16 in the box 10 around the metal casing and the violet ray tube 11 and by means of the electrical discharge created by the violet ray tube and the casing the air is changed to 50 ozone and is carried by the pipe 8 to the T 7 where it mixes with the burned gas conveyed to the T 7 by the pipe 9. From the T 7 this mixture is conveyed by the pipe 4 and its L-shaped end to the bottom of the 55 receptacle 2 and out through the perforations 6 into the water in the receptacle 2 through which it percolates and is conveyed through the pipe 60 to the inlet pipe 61

where it mixes with the combustible mixture formed by the carburetter. It has been found that by the use of the mixture formed by combining the air passed over the violet ray tube with a portion of the exhaust gas from the engine and then passing this mixture through water that a considerable leaner 60 mixture of gasoline and air can be used through the carburetter and also that the formation of carbon in the cylinders and on the spark plugs is practically eliminated.

Other modes of applying the principle of 70 my invention may be employed instead of the one explained, change being made as regards the mechanism herein disclosed, provided the means stated by any of the following claims or the equivalent of such stated 75 means be employed.

I therefore particularly point out and distinctly claim as my invention:—

1. In a device of the character described in combination with an internal combustion 80 engine having inlet and exhaust manifolds, a tank adapted to contain water at constant level, a pipe attached to said exhaust manifold adapted to convey burned gas to the bottom of said water tank, an ozonizer, a pipe attached to said ozonizer adapted to convey ozone to said first pipe between said exhaust chamber and said water tank, means in said water tank adapted to permit such burned gas and ozone mixture to percolate 85 through such water in said tank, and a pipe attached to said water tank adapted to convey such mixture to the intake chamber of 90 said internal combustion engine.

2. In a device of the character described 95 in combination with an internal engine having an exhaust pipe, an intake pipe and a carburetter, a water tank adapted to contain water at a constant level, a pipe connected to the exhaust pipe of said internal combustion 100 engine adapted to convey burned gas into said water tank below the level of the water therein, an ozonizer, means for operating said ozonizer, a pipe connected to said ozonizer adapted to convey ozone to said burned 105 gas conveying pipe outside of said water tank, means within said water tank adapted to permit such burned gas and ozone mixture to percolate through such water in said water tank, and a pipe attached to said 110 water tank above such water level adapted to convey the mixture in said water tank to the intake pipe above the carburetter.

Signed by me, this 4th day of December, 1920.

WALTER W. GROOMS,
